HAIR WAVING APPLIANCE

Georg Ströher, Rothenkirchen, Germany

Application November 7, 1936, Serial No. 109,637
In Great Britain October 5, 1936

1 Claim. (Cl. 219—24)

This invention relates to hair waving appliances, and refers more particularly to a heating clamp consisting of a ceramic material and used for the purpose of producing permanent hair waves.

The customary procedure in making permanent hair waves is to wind a strand of hair upon a rod and then to place an electrical heating element or clamp over the strand for the purpose of heating or baking the wound strand of hair. This heating element or clamp is usually cylindrical in form and is sometimes made of a plurality of concentric cylinders or layers, the heating wires being situated between these layers. Such constructions are expensive, heavy, easily breakable and inconvenient to manufacture.

An object of the present invention is the provision of a heating clamp which is simple in construction, inexpensive to manufacture and which will distribute the heat generated by the heating resistances evenly and uniformly over the entire wound strand of hair.

A further object is the provision of a heating clamp which is comparatively very light in weight and which will constitute an excellent accumulator of heat generated by the heating resistances.

The above and other objects of the present invention may be realized through the provision of a heating clamp comprising a pair of substantially semi-cylindrical portions or jaws, each of which consists of one piece of ceramic material and is provided with cavities or longitudinal and/or transverse grooves or bore holes containing the heating wires. If desired, the heating wires may be insulated from the ceramic jaws. The handle portions of the clamp may be provided with electrical contact prongs connecting the heating wires to a source of electrical energy.

Any desired number of heating wires interconnected in any suitable manner may be arranged within the cavities provided in the ceramic jaws.

The invention will appear more clearly from the following detailed description when taken in connection with the accompanying drawings showing by way of example preferred embodiments of the inventive idea:—

In the drawings:—

Figure 1 shows in side elevation a clamp constructed in accordance with the principles of the present invention;

Figure 2 is a sectional view of one of the jaws of the clamp on a larger scale;

Figure 3 is a cross-section through the clamp;

Figure 4 shows in end elevation a clamp of a somewhat different form;

Figure 5 is a side view of the clamp shown in Fig. 4;

Figure 6 is a section through one of the jaws of the clamp shown in Figs. 4 and 5; and

Figure 7 is a cross-section through this clamp.

The clamp shown in Figures 1, 2 and 3 of the drawings comprises two jaws 8 and 9 which consist of a ceramic material. A handle portion 10 is firmly connected with the jaw 8 by any suitable means 11, while a second handle 12 is connected with the jaw 9 by the means 13. The handles 10 and 12 are provided with ear portions 14 and 15 carrying the pivot 16 around which the jaws 8 and 9 may be swung. Any suitable spring not shown in the drawings may be used for maintaining the clamp in the closed position.

As shown in Figure 2, the handle 12 comprises a bore hole through which the wires 17 and 18 extend. The handle consists preferably of a central portion 19 and two end portions 20 and 21 which are held together by a connecting bolt 22, provided with end disks 23 and 24 which are situated in cavities formed in the pieces 20 and 21 and are in engagement with washers 25 and 26, respectively.

A prong 27 is carried by the handle 12. The lower end of the prong 27 is situated within a cavity provided in the handle 12 and is conductively connected to the wire 17.

As shown by broken lines in Fig. 2, a socket 28 which is connected by a wire 29 to a source of electrical energy not shown in the drawings, may be placed over the prong 27.

An insulated wire 30 is electrically connected with the wire 18, the lower end of the wire 30 being situated in a bore hole formed in the handle 12.

As shown in Figs. 1 and 3, the handle 10 is substantially similar in construction to the described handle 12. The handle 10 carries a prong 31 and supports the opposite end of the wire 30 which is connected to a wire 32 situated within the interior of the handle 10.

In accordance with the present invention, each of the jaws 8 and 9 is made of one piece of ceramic material, such as clay or porcelain. The jaw 8 is provided with a cut-out portion 33 which is formed upon the inner surface of the jaw 8. The jaw 9 is provided with a similar cut-out portion 34. A heating resistance having the form of a coil or winding 35 is situated within the cut-out portion 34 of the jaw 9. The two ends of

the heating wire 35 are connected to the wires 17 and 18, respectively.

In the device illustrated in the drawings, the heating wire 35 is carried by an insulation piece 36 which is situated within the cut-out portion 34. As previously mentioned, the insulation piece 36 may be dispensed with, whenever necessary.

A heating coil 37 which is situated opposite the heating coil 35 is carried by insulation piece 38, which is situated within the cavity or cutout portion 33 provided in the jaw 8. The heating coil 37 is connected with a wire 32 leading to the insulated wire 36 and to the wire 39 leading to the prong 31.

An important distinction between the described construction and the one shown in Figs. 4 to 7 of the drawings is that in the latter the heating wires 40 to 45 are situated within bore holes 46 to 51 provided in the interior of the jaws 52 and 53, each of which consists of one piece of ceramic material.

An angular support 54 is connected by bolts 55 with the jaw 52. A handle 56 is connected by bolts 57 to the support 54. A similar support 58 is connected by bolts 59 to the jaw 53 and is also connected by bolts 60 to the handle 61.

The handles 56 and 61 comprise ears 62 and 63 carrying a pivot 64 around which the jaws 30 may be swung.

In the example illustrated, the jaw 52 comprises two cylindrical projections 65 and 66 which carry the prongs 67 and 68. The jaw 53 comprises two similar projecting portions 69 and 70 carrying the two prongs 71 and 72. The wires 43, 44 and 45 may be inter-connected in parallel by means of the wires 73 and 74 which are located in suitable grooves and which are connected to the prongs 71 and 72, as indicated in 40 Figures 6 and 7.

The wires 40, 41 and 42 carried by the jaw 52 may be interconnected in parallel with each other and connected to the prongs 67 and 68 in a similar manner.

The inner surfaces of the jaws 52 and 53 may be covered by metallic layers 70 which are applied to the ceramic jaws by galvanization or any other suitable means. These metallic layers will concentrate the heat on the inside of the shell and will also strengthen the same.

The described clamps may be used in substantially the same manner as those known in the art.

When the clamp shown in Figures 1 to 3 of the drawings is placed over a wound strand of hair, the operator will connect the prongs 27 and 31 to a source of electrical energy, thereby heating the wires 35 and 37. This heat will be transmitted to the ceramic jaws 8 and 9 which will accumulate the heat and transmit it uniformly 15 and evenly to the wound strand of hair.

When the clamp shown in Figures 4 to 7 is used, the operator may connect the four prongs 67, 68, 71 and 72 to the same source of energy or to different sources. With this construction it is 20 possible to supply heat to only one of the two jaws, thereby regulating the baking process.

The described clamps are very cheap to manufacture, since they do not consist of concentric layers and do not require expensive insulation 25. The ceramic jaws of these clamps constitute an excellent accumulator of the heat generated by the heating resistance. Another important advantage of these clamps is that they are extremely light in weight so that a large number of such 30 clamps may be used upon the head of a person without causing inconvenience or discomfort.

What is claimed is:—

A heating clamp for hair waving purposes comprising a pair of articulated jaws, each of said jaws consisting of a single piece of ceramic material, at least one longitudinal recess in each of said jaws at the interior side thereof, a heating element disposed in said recess, a metal layer on the interior surface of each of said ceramic jaws entirely covering said heating element, said metal layer being formed integral with said jaw and being devoid of extraneous fastening means. 35 40
